UNITED STATES PATENT OFFICE.

WALTER HAHNEMANN, OF KIEL, GERMANY, ASSIGNOR TO THE FIRM SIGNAL
GESELLSCHAFT M. B. H., OF KIEL, GERMANY.

UNDERWATER WAVE TELEGRAPHY.

1,377,129.

Specification of Letters Patent.

Patented May 3, 1921.

Application filed January 2, 1915. Serial No. 306.

To all whom it may concern:

Be it known that I, WALTER HAHNEMANN, a subject of the Emperor of Germany, and residing at Kitzeberg, b/Kiel, c/o Signal 5 Gesellschaft m. b. H. Kiel, Werk Ravensberg, Germany, have invented certain new and useful Improvements in Underwater Wave Telegraphy, of which the following is a specification.

- 10 This invention appertains to trans-marine radiotelegraphy, and one object of the same is to provide a system of trans-marine radiotelegraphy which may be employed on stations one or both of which are located on 15 shore or on ships at sea, wherein the elements employed for radiating the electrical energy are disposed below the surface of the water, and the radiotelegram transmitted through the latter.
- 20 Another and further object of this invention is to provide a system of trans-marine radiotelegraphy which is particularly applicable to naval vessels inasmuch as the elements for radiating the electrical energy are 25 disposed below the surface of the water and consequently are not exposed to destruction when said vessels are involved in a naval engagement.

- Another and still further object of this invention is to reduce the cost of constructing 30 a radiotelegraph station by eliminating the extremely high aerial towers now employed and substitute the underwater radiating elements proposed by this invention.
- 35 Another and further object of this invention is to provide a system wherein the possibility of a vessel having its radio system crippled by reason of damage to aerial is reduced to a minimum.

- 40 With these and other objects in view, my invention consists of certain novel features of construction, combination and arrangement of parts to be hereinafter set forth and claimed.

- 45 In the accompanying drawings—

Figure 1 represents a portion of a ship partly in section showing a high frequency transmitter mounted thereon;

Fig. 2 is a similar view showing a receiver;

Fig. 3 is a diagrammatic view showing the dissemination of the electric waves in the water.

Heretofore it has been customary in systems of radiotelegraphy to have the ele-

ments employed for radiating the electrical energy, in other words, the antenna, disposed high above the station, if the latter is on the shore, or the ship as the case may be. This, however, has proved objectionable in 60 that the vital part of the system is exposed and if destroyed the result is that the entire system is temporarily disabled and this is particularly true with respect to naval vessels involved in a naval engagement, inasmuch as the aerial tower is in such a position as to be easily and quickly destroyed.

Now it is to eliminate the various disadvantages heretofore mentioned with respect to the trans-marine radiotelegraphy 70 systems now in use, and to provide a system in which the elements employed for radiating or collecting the radiated electrical energy, in other words, the antenna is disposed below the surface of the water and 75 consequently comparatively free from destruction, which thus makes it impossible to cripple the system by damage to the antenna.

The difficulty however, which up to the 80 present has prevented the practical use of underwater radiotelegraphy has been due to the fact that the usual frequencies of the electrical source utilized in connection with the ordinary systems of radiotelegraphy 85 cannot overcome the ohmic resistance of the sea water, furthermore it is a well known principle of radiotelegraphy that the relation of the ohmic resistance to the capacity reactance plays a part in so far as with the 90 rising frequency in general the value of the relation of the latter with respect to the ohmic resistance sinks. If therefore it is possible to make the capacity reactance equal to or smaller than the ohmic resistance 95 then communication under water by means of electrical waves is possible.

It will thus be seen that by an increase in the current frequency it is possible to diminish the reactance of the conducting medium to an unlimited extent the ohmic resistance being dependent on the frequency of the current. Hence the higher the frequency, the smaller becomes the reactance and consequently a much greater part of the 100 electric energy is then transmitted by dielectric displacement and is no longer subjected to loss of energy by ohmic resistance.

As the losses of energy in case of dielec- 110

tric transmission for the above mentioned reason is considerably lessened, then in case of transmission by pure current conduction, a considerable increase in range is obtained 5 presupposing that success is obtained in radiating considerable quantities of energy in the form of very short waves.

The gist of this invention resides in the fact that the frequency of the electric current is so calculated that the reactance of 10 the medium, that is the sea water, becomes equal to or less than the ohmic resistance of the medium. This requirement is obtained owing to the fact that the frequency adopted 15 for use is selected at not less than 3×10^8 vibrations in a second because as calculation shows, at this frequency the specific resistance is already approximately equal to the specific reactance.

20 Thus it will be understood that for carrying out this invention it is only necessary to apply to the ship a generator which generates frequencies of the order and magnitude stated.

25 Therefore, pursuant to the above, if the station or ship be provided with an alternating current generator having its current frequency so gaged as to cause the reactance of the medium, in this case the sea water, to 30 be equal to or smaller than the ohmic resistance of the medium then it will be possible to transmit radiotelegrams through the water as they are now transmitted through the air. The generator to produce

35 proper results must, it is found, produce a current having a frequency greater than 3×10^8 per second. In this connection it is to be understood that the radio energy is transmitted to the water by suitable radiating elements arranged for instance on

40 the bottom of the ship, while on the receiving station, which may be another ship, a corresponding receiver is arranged, which absorbs the radio waves and transmits them

45 to a detector suitable for frequencies of the above mentioned magnitude.

In the embodiment illustrated, an arrangement for practically carrying out the invention is shown which includes a transmitter which is housed in the double bottom of a ship preferably between two beams A, and comprises two radiators O, O formed in accordance with the known Hertz oscillators having one of their ends thereof dis-

55 posed in a receiver B filled for instance with petroleum P and with their other ends extending into the water outside. The oscillators O are connected to the generator G by the leading in or conducting wires Z which

60 pass through the ship's bottom W and are surrounded by suitable insulation at their points of passage through the bottom. Between the radiators O, O which serve as electrodes, there passes a luminous arc which 65 generates very high frequency waves after

a manner of the well known Dudell phenomenon. In the conductors Z there are formed large choker spools D for the purpose of preventing an overflow of waves to the generator. In case the ship is already 70 provided with a conduction net-work of sufficient high tension, say about 500 volts, the transmitter device may also be connected in the same or a suitable transformer may be used.

75 The receiving device shown in Fig. 2 is similar to the transmitter and has disposed below the bottom of the ship W electrodes E similar to the oscillators of the transmitter. These electrodes have one of their 80 ends disposed in a receiver B' secured to the bottom of the ship and filled with petroleum P' while their other ends project into the water. Between the ends of the electrodes E which are arranged in the petroleum receiver there is provided a thermoelement T connected with a galvanometer M by the conductors Z' which extend through the ship's bottom and have insulating material arranged around them at the points 85 where they pass through said bottom.

90 It is to be understood that both the transmitter and the receiver may be arranged on the same ship if desired as is shown diagrammatically in Fig. 3. The waves V sent 95 out from the transmitter O' spread out into the water in the form shown in Fig. 3 and as soon as they reach the receiver E' may be recognized by the deviation of the galvanometer connected with it.

100 The principle upon which this invention operates may be more readily understood by referring to the Ohm's law for alternating current which is represented as follows:

$$J = \frac{E}{\sqrt{W^2 + \left(wL - \frac{1}{wC}\right)^2}}$$

105 In this equation

$$\sqrt{W^2 + \left(wL - \frac{1}{wC}\right)^2}$$

110 denotes the impedance which a tension E has to overcome to produce a current J. The value w is the product of 2π and the number n of quiet oscillations per second. If the 115 conducting path is of such a nature that the current does not produce a magnetic field, then L will be zero.

120 However, if the conducting path is of such a nature that no amount of electricity can remain quiet upon it, then C, the capacity, is equal to zero. That is to say, the conducting path is capacity free. In these cases the values wL and $\frac{1}{wC}$ of which the first 125 means the inductance caused by self-induction, while the latter denotes the reactance caused by capacity can be considered fallen away or disappeared. The self-induction L 130

and consequently the value wL of the foregoing equation does not now come into question. The ohmic resistance W is, as is apparent from the equation, absolutely independent of the value $w=2\pi n$ of the alternating current. The reactance $\frac{1}{wC}$ of the 10 equation however, which as stated above, also possesses the characteristics of a resistance, is directly dependent upon the magnitude of the capacity C as well as upon the magnitude of the value W and in such a manner that this value will become less when the capacity increases and also when 15 the frequency rises. In the above cited example it will be seen that we only have to observe now

$$20 \quad J = \frac{E}{\sqrt{W^2 + \left(\frac{1}{wC}\right)^2}}$$

in which the values W and wC remain constant. If one now considers the relation of 25 the values W and wC , it will be found that the value of $\frac{W}{wC}$ falls with the rising 30 value of w . Obviously, one can consider in a conducting medium capable of great all-around expansion in all directions and a high dielectric constant, that an alternating current can be divided into two currents, one of which is propagated through ordinary conduction while the other would propagate 35 itself similar to the manner in which an alternating current would pass through a condenser filled with an insulator. For the first named current the value W is controlling for the magnitude of resistance, and for the last named current it is controlling 40 for the value $\frac{1}{wC}$. In $w=2\pi n=0$, the value $\frac{1}{wC}$ becomes infinite. It will thus 45 be seen that with a very high n and also a very high w the value of $\frac{1}{wC}$ when compared with the value W is very small.

It naturally follows that in a rising frequency more and more current must spread 50 out on the last mentioned path and furthermore, on this path all the more current must spread out, the smaller the value of the equation becomes. However, inasmuch as in this spreading out process much smaller 55 losses arise than with the ordinary conducting path (due to absorption), it naturally follows that with the rising frequency, all other conditions being equal, the wave spreading must become better. 60

I claim my invention—

1. A system of submarine radiotelegraphy having high frequency transmitting and receiving elements disposed beneath the surface of the water, and utilizing an alternating current of such frequency as to cause the capacity reactance of the transmitting medium at its highest to be equal to the ohmic resistance of said medium. 65

2. A system of submarine radiotelegraphy having high-frequency transmitting and receiving elements disposed beneath the surface of the water, and utilizing an alternating current of such frequency as to cause the capacity reactance of the transmitting 75 medium to be smaller than the ohmic resistance of the medium.

3. A system of submarine radiotelegraphy having high-frequency transmitting and receiving elements disposed beneath the surface of the water; and utilizing an alternating current having a frequency of at least 80 3×10^8 per second.

4. A system of submarine radiotelegraphy having high-frequency transmitting and receiving elements beneath the surface of the water and utilizing an alternating current having a frequency of more than 3×10^8 85 per second.

In testimony whereof I affix my signature 90 in presence of two witnesses.

WALTER MAHNEMANN.
